UNITED STATES PATENT OFFICE.

AMOS SHEPARD, OF SOUTHBURG, CONNECTICUT.

DESIGN FOR DRAWER-PULL.

Specification forming part of Design No. 7,075, dated December 23, 1873; application filed December 15, 1873.
[Term of Patent 7 years.]

To all whom it may concern:

Be it known that I, AMOS SHEPARD, of Southbury, in the county of Hartford and State of Connecticut, have invented and produced a new Design for a Drawer-Pull, of which the following is a specification:

The nature of my design is fully represented in the accompanying photographic illustration, to which reference is made, and in which—

Figure 1 is an edge view of a drawer-pull embodying my design, and Fig. 2 is a front view of the same.

The base A is in the form of one side and the two ends of an ellipse. The pull proper projects forward from the base A, and at its

front B assumes the form of an ellipse, as is clearly shown in the drawing. The general surface of the front B may be slightly rounded, as shown, but should be straight one way, preferably in its longitudinal direction, as shown in Fig. 1. I prefer to place upon the front B ornamental work in relief, but this is not essential to my design.

I claim as my invention—

The design for the front of a drawer-pull, as described, and shown in the drawing.

AMOS SHEPARD.
